SLICING MACHINE

Adam J. Manxi, Chicago, Ill.

Application November 20, 1929

Serial No. 408,469

6 Claims. (Cl. 146—166)

This invention relates to improvements in slicing machines and it consists of the matters hereinafter described and more particularly pointed out in the appended claims.

5 The primary object of the invention is to provide a simple and efficient machine especially adapted for use in restaurants, hotels, sandwich stands and the home for cutting entire loaves of bread, meat rolls and the like into a plurality of 10 slices at one operation, which slices may be quickly removed as a stack ready for serving.

Another object of the invention is to provide a machine of this kind which may hold a number of loaves of bread, meat rolls and the like in 15 reserve ready for future slicing as occasion demands.

These objects of the invention as well as others together with the many advantages thereof will more fully appear as I proceed with my specification.

20 In the drawings:—

Fig. 1 is a longitudinal vertical sectional view through a slicing machine embodying my invention, as taken on the line 1—1 of Fig. 2.

25 Fig. 2 is a transverse vertical sectional view through the improved slicing machine as taken on the line 2—2 of Fig. 1.

Fig. 3 is another transverse vertical sectional view through the same as taken on the line 3—3 30 of Fig. 1.

Fig. 4 is a perspective view of one of a plurality of holding arms embodied in my improved slicing machine.

Fig. 5 is a perspective view of one of a number 35 of spiders embodied in the improved machine.

Fig. 6 is a perspective view of a certain lever associated with a set of arms such as shown in Fig. 4.

In general my improved machine which as 40 shown herein is especially adapted for slicing leaves of bread, includes a supporting base upon which a longitudinal extending shaft is journaled for rotation. On said shaft is fixed a plurality of sets of hinged, substantially circular arms, each set being adapted to receive and surround a loaf to hold it in place. On the base below said shaft is a plurality of transversely disposed, longitudinally spaced blades each having a cutting edge disposed eccentric with respect to 45 the shaft so that when the shaft is turned, a loaf is brought into engagement with the blades to be cut into a plurality of slices. After passing beyond the cutting edge of the blades, the slices are retained by said arms against separation until 50 said arms are released therefrom, when the slices

may be removed as plurality or stack ready for use.

Referring now in detail to that embodiment of the invention illustrated in the drawings, 1 indicates as a whole the frame or base of the machine which comprises, upright end frame members 2 and 3 respectively and upright front and rear walls 4 and 5 respectively, fixed to said end frame members in any suitable manner. Said front and rear walls, each includes a horizontally disposed, inwardly extending bottom flange 6 terminating in a vertically depending flange 7 so as to leave an open space between said flange 7—7 as best shown in Fig. 2.

Extending transversely of said frame is a plurality of longitudinally spaced, fixed blades 8—8 each having a cutting edge 8^a disposed eccentrically with respect to a certain shaft, to be mentioned later. Said blades are spaced apart, a distance corresponding to the desired thickness of slices to be made and in each end of each blade as well as in the bottom edge thereof are notches 9 and 10 respectively. The notches 9 of the several blades receive combined holding and guide bars 11—11 fixed to the associated front and rear walls 4 and 5 respectively, while the notches 10—10 receive combined holding and guide bars 12—12, one fixed to and rising from each flange 7 before mentioned. The end frame members 2 and 3 respectively are further connected together by tie rods 13 which extend through suitable openings provided therefor in the several fixed blades 8. The cutting edge 8^a of each blade which is formed in the front top portion thereof is curved or substantially semi-circular and preferably said edge is scalloped as shown to improve its cutting action.

Each end frame member 2 and 3 respectively is formed at its mid portion with an upright extension that terminates in a bearing 2^a and 3^a respectively, to receive a longitudinally extending, horizontally disposed driven shaft 14. One end of said shaft is extended beyond its associated bearing 3^a and has there fixed to it a spur gear 15. Said gear is enclosed in a guard 16 fixed to the end frame member 3 and in said guard is journaled a shaft 17 parallel with and below the said end of the shaft 14. On said shaft 17 within the guard is fixed a spur pinion 18 meshing with the gear 15 and on the shaft 17 outside of the guard is fixed a crank 17^a by which the shaft 14 may be rotatively driven in the desired direction. Of course, it is apparent that any desired means may be employed for driving the shaft 14, other than that just described.

On the shaft 14 is provided a plurality of longitudinally spaced spiders 19—19 with one of such spiders disposed in the plane of each cutter blade 8. Each spider 19 as shown herein has three arms 20 and in each arm is a rectangular opening 21. Said arms are all secured to the shaft in said spaced relation by a spline 22 as best shown in Figs. 1 and 3 respectively. A shaft 23 of rectangular cross section extends through the arms 20 of said spiders and mounted on each of said shafts is a loaf holding means, each in itself comprising a set of loaf holding members 24 disposed in planes between those of the several spiders 19. As the holding members of each set thereof are all alike, a detailed description of one will suffice for all. Each holding member comprises a pair of semi-circular arms 25 and 26 respectively pivotally connected together as at 27. The arm 25 has a rectangular opening 28 through which the associated shaft 23 extends. The free ends of all the arms 26 of a set of arms are connected together by a longitudinally extending bar 29 (see Fig. 3) and this bar has a cylindrical extension 30 at that end beyond the right hand endmost arm of the set. Each arm 26 is also provided with one or more inwardly extending pointed prongs 31.

Fixed to that portion of the right hand endmost arm 25 of each set is a ratchet plate 32 and on each bar extension 30 is pivoted a lever 33 best shown in Fig. 6. Said lever includes a tooth 34 to engage with the teeth of the associated plate 32 so as to detachably lock the free end of the arms 26 to the arms 25 as is apparent. A spring 35 associated with each lever, holds the same in a position with its tooth in engagement with the desired tooth of the ratchet plate 32 and said lever is provided with a bent over end portion 36 to limit its movement in the other direction when the tooth 34 is released from the tooth of the ratchet plate 32 with which it is engaged.

For ease in following the operation of the machine I have applied to Figs. 1 and 2 the reference characters A, B and C respectively, which are employed to indicate "positions" only. Assume now that it is desired to slice but a single loaf of bread. The lever 33 of the set of holding members 24 in position A are released so that the arms 26 may be swung about the pivots 27 away from the arms 25 whereby a loaf of bread may be positioned upon said arms 25 after which the arms 26 are swung downwardly and are locked by the lever 33 and ratchet plate 32. When the arms thus surround the loaf, the prongs 31 bite into the loaf and prevent its movement.

The crank or handle 17^a is now turned clockwise and this will through the pinion 18 and gear 15 will rotate the shaft 14 counter clockwise and at a slower speed. As the set of arms formerly in position A now approach the cutting edges 8^a of the blades 8 the loaf is cut with a shearing action, passing through positions B and C, back to A. When the sliced loaf again reaches position A, the arms 26 are released and the slices of bread may be simultaneously removed as a stack, ready for serving.

Should the machine be employed where large quantities of sliced bread are required, as in restaurants, hotels and other public eating establishments, the first loaf is placed in the holder when in position A and the handle is turned to bring it to position B thus moving the holder formerly in position B to position C and the holder formerly in position C to position A ready to receive a second loaf and so on. In this manner

a plurality of loaves are positioned ready for slicing as occasion demands and when the sliced loaf reaches position A it is removed and another loaf is positioned for future slicing.

Such crumbs as are formed in the slicing of the bread may drop down through the space between the members 12—12 upon a tray (not shown) which may be placed in position beneath the base 1 to catch the same.

By my improved machine not only bread may be readily sliced, but also edible articles such as meat loaves and rolls may be cut into the desired slices. The machine may be of any desired length, is fast and positive in operation and is simple in construction so that it will not readily get out of order.

While in describing my invention, I have referred in detail to the form, arrangement and construction of the several parts thereof, the same is to be considered merely as illustrative of one embodiment of the invention so that I do not wish to be limited thereto except as may be specifically set forth in the appended claims.

I claim as my invention:—

1. A slicing machine embodying therein a plurality of laterally spaced fixed, cutter blades, a rotative shaft disposed above and transversely of said blades, a plurality of article holding means fixed to said shaft and movable in the rotation of said shaft to present said articles to said blades, 100 each holding means comprising a plurality of fixed arms, other arms pivoted at one end to said fixed arms and coacting therewith to hold said article therebetween the other end of all of said other arms being connected together. 110

2. A slicing machine embodying therein a plurality of laterally spaced fixed cutted blades, a rotative shaft arranged transversely of said blades, a plurality of spiders fixed to said shaft in the plane of said blades, a plurality of arms fixed to 115 said spiders in planes between those of said blades and other arms operatively engaged at one end with an associated fixed arm the other ends of all of said other arms being connected together and adapted to be detachably connected to said fixed 120 arms.

3. A slicing machine, a frame including end members, a plurality of laterally spaced, fixed cutter blades on said frame between said end members, a shaft arranged transversely of said 125 blades and journalled in said end members for a rotative movement and a plurality of article holding means fixed to said shaft for rotation and each including laterally spaced pairs of co-acting pivotally connected arms to embrace the 130 article for holding the same in the presentation thereof to said blades one end of one arm of each pair being fixed with respect to said shaft and the other end of the other arms of said pairs being fixed with respect to said shaft and the 135 other end of the other arms of said pairs being connected together.

4. In a slicing machine of the kind described, article holding member, comprising a shaft, a plurality of sets of laterally spaced members including arms, some of the arms of one set being fixed at one end with respect to the shaft, means pivoting one end of the other arms of said set to the other end of the first mentioned arms means connecting the other end of said other arms in each set together and means for detachably connecting said other end of said second mentioned arms to the fixed end of the first mentioned arms. 145

5. In a slicing machine of the kind de- 150

scribed, article holding means comprising a rotatable shaft, a plurality of sets of laterally spaced members, each including a pair of curved arms, one end of one arm of each member being fixed 5 with respect to said shaft, means pivoting one end of the other arm of each member to the other end of the first mentioned arm, means connecting the other end of all of said other arms in said set together and means for detachably connecting the last mentioned end of said other arms with respect to the first mentioned end of the first mentioned arms.

6. A slicing machine embodying therein, a

frame, a shaft journalled at its ends therein, a plurality of fixed cutter blades arranged in spaced relation in said frame below said shaft and each having a cutting edge, a plurality of article holding members arranged in planes between 80 said blades, and each including curved arms pivoted together at one end, means for securing the other end of one arm with respect to the shaft, means for connecting the other ends of all of said other arms together and coacting means on the 85 last mentioned ends of both arms for securing them in article encircling relation.
